UNITED STATES PATENT OFFICE.

GEORGE W. WILLEY, OF PHILADELPHIA, PENNSYLVANIA.

CAR-FENDER.

SPECIFICATION forming part of Letters Patent No. 569,699, dated October 20, 1896.

Application filed July 27, 1895. Serial No. 557,340. (No model.)

To all whom it may concern:

Be it known that I, GEORGE W. WILLEY, a citizen of the United States, residing at Philadelphia, in the county of Philadelphia and State of Pennsylvania, have invented certain new and useful Improvements in Car-Fenders, of which the following is a specification, reference being had therein to the accompanying drawings.

10 The invention relates to an improved fender of the "pick-up" class, and is especially adapted for use upon cars operated by electric, cable, or other power.

15 The object is to produce a device of this character, of simple and inexpensive construction, by which the removal of obstructions from the track will be effected with safety and without inflicting serious injury.

20 With these objects in view the invention consists in certain novel features and combinations and arrangements of parts to be hereinafter described and claimed.

25 In the accompanying drawings, forming part of this specification, and wherein like letters of reference indicate corresponding parts in the several views, Figure 1 is a view in perspective of one embodiment of the invention applied. Fig. 2 is a view in central vertical longitudinal section, showing by dotted lines the several positions the fender may be made to assume. Fig. 3 is a view in 30 plan. Fig. 4 is a central vertical section of the releasing device. Fig. 5 is a view in detail of one of the fender-actuating springs. Fig. 6 is a view in detail of the cushioned extremity of one of the V-shaped projections, and Figs. 7 and 8 are similar views of a modified form of releasing device.

35 In the drawings, A represents a portion of a car; a, the forward end thereof, to which the fender is applied, and a² the truck-frame.

40 B represents the fender, which consists, essentially, of a skeleton frame b, movably mounted between two forward-projecting bars or extensions of the car-truck by being pivoted in the slotted extremities thereof. This frame comprises a series of diverging bars b³, suitably spaced and having a limited movement about a common axis b⁴. From 45 the axis the bars project forward and are curved downward toward the road-bed, where they terminate in apertured heads, and upon

engagement with small obstructions upon the track, such as stones, &c., will yield at the pivot-point and pass over them without strain or injury to the structure. The opposite extremities b⁶, lying beneath a net of metal or other suitable material, extend rearward from the axis and are attached to or form part of a transversely-disposed bar 55 b⁷, which is movable between the truck extensions b⁸ under the influence of two or more downward-acting springs b⁹.

Secured in the apertured heads of each of the bars are two rubber-covered helical 65 springs b¹⁰, which are carried upward upon opposite sides thereof and secured to the axial rod at points midway of the bars, so as to form a series of approximately V-shaped recesses b¹¹, which, upon engagement with 70 man or beast obstructing the track, are designed to receive and clamp the limbs of the body, the latter being then elevated by mechanism to be described later on. Covering the apertured heads are tips b¹², which may 75 be of hard or soft rubber or other material and serve to break the force of the blow of collision, also as guides to facilitate the entrance of objects into the recesses.

C represents a releasing device for the fender, which consists of a tubular casing c, arranged vertically in the rear of the dash and having centrally mounted therein a rotatable rod c², upon the upper end of which a hand-wheel c³ is fixed. The opposite extremity of 80 this rod or shaft terminates in an angularly-projecting lug c⁴, which is designed to be passed through an opening in the transverse rod connecting the fender-bars. Within the tubular casing a number of annular lugs or 85 flanges c⁵ are formed, and each flange is notched, as at c⁶, for the passage of a lug c⁷ upon the releasing-shaft. These notches are aligned with a recess c⁸, formed in the wall at the upper end of the tubular casing, into 90 which a second lug or projection c⁹ from the shaft is designed to enter.

95 In use the fender lies, normally, with the rubber-tipped projections clear of road inequalities, and is sustained in this position 100 against the action of the downward-acting spring by the lug upon the releasing-shaft engaging the upper flange within the casing. If for any reason it should be found neces-

sary or desirable to partially elevate the fender, the motorman, by rotating the shaft until the lug passes through the notch of the flange, may then cause it to lock upon the second or 5 next-lowest flange, and thereby permit the springs to catch and raise the fender a distance proportionate to the downward movement of the shaft. When, however, the body of a man, for example, is caught, it is preferable that the fender should be immediately 10 elevated, and to effect this the motorman, by means of the hand-wheel, rotates the shaft until the lug passes through the notch of the flange, and, since the notches are alined, 15 upon releasing the rod, the springs, being free to catch, draw the shaft downward until the second lug becomes seated in the recess of the tubular casing, and thereby elevate the fender to a horizontal position, as is clearly 20 shown in Fig. 2. Upon giving the hand-wheel a full half-turn the lower terminal lug and the actuating-springs become disengaged from the bar, and the entire device may then be swung upward against the dash, as is also 25 shown in the same figure of the drawings.

Referring to Figs. 7 and 8, a modified form of releasing device is illustrated and consists in providing the tubular casing with a rotatable cover and the releasing-shaft with diametrically opposite fins at or adjacent the upper end. These fins work through an opening in the cover and are enlarged at their upper ends to form stops and thereby limit the downward movement of the shaft. Projecting upward from the cover is an arm slotted 30 to receive the end of a lever, which is pivoted to the releasing-shaft and by means of which the shaft may be more readily elevated, its action being otherwise as above described.

40 It will be understood that I do not wish to limit myself to the exact construction and arrangement of parts as herein illustrated

and described, since innumerable changes may be made without departing from the spirit of my invention.

45

Having thus fully described my invention, what I claim as new, and desire to secure by Letters Patent, is—

1. The combination in a fender, of a base or support, a series of bars carried thereby, 50 and springs supported by said bars, said springs forming approximately V-shaped recesses for engagement with obstructions upon the track, substantially as specified.

2. The combination in a fender, of a series of forwardly-projecting bars, and covered springs connected to the front ends of said bars, said springs being arranged at an angle to each other and forming a series of approximately V-shaped recesses for engagement 6c with obstructions upon the track, substantially as specified.

3. The combination in a fender, of a series of forwardly-projecting bars, a spring arranged on each side of and carried by said 65 bars, said springs being so mounted as to form between them a series of approximately V-shaped recesses for engagement with obstructions upon the track.

4. The combination in a fender, of a frame, 70 means for raising and lowering the same, a series of forwardly-projecting bars forming part of said frame, a transverse pivot-rod to which said forwardly-projecting bars are pivoted, and springs arranged on each side of 75 said bars, and connected at one end to the forward end of the bars, and at the opposite end to said pivot-rod, substantially as specified.

In testimony whereof I affix my signature in the presence of two witnesses.

GEORGE W. WILLEY.
